FIG. 1

FIG. 3

FIG. 2

FIG. 4

FIG. 1 is a front elevation view of a bombe chest cabinet in accordance with the present invention;

FIG. 2 is a top plan view thereof;

FIG. 3 is a bottom plan view thereof; and

FIG. 4 is a left side elevation view thereof.

The undisclosed rear elevation is identical to the front elevation of FIG. 1 except that the clip shown in FIG. 1 does not appear in the rear elevation view. The right side elevation view not shown is a mirror image of the left side elevation of FIG. 4.

I claim:

The ornamental design for a bombe chest cabinet, substantially as shown and described.
